UNITED STATES PATENT OFFICE.

SOPHOCLES DEMETRIUS VERGONIS, OF NEW YORK, N.Y.

REGISTERING COLLECTION BOX.

Application filed November 23, 1923. Serial No. 676,622.

This invention relates to coin registering collection boxes and the like and more particularly to a novel and improved portable container or carrier and particularly designed for use by collectors or agents of charitable institutions, societies, or organizations in which an absolutely accurate register must be kept of funds received.

One of the objects of my invention is to provide a collection box having a removable coin receiving receptacle divided into a series of compartments, which receptacle may be removed by opening a locked door or closure.

Another object of my invention is to provide a collection box having a coin receptacle therein including a series of registering devices whereby the number of coins deposited can be ascertained and checked against the number of coins found in the receptacle.

A further object of my invention is the provision of a coin receptacle and registering means therefor wherein the register is actuated upon the insertion of a coin the device including means for gaining access to each of said registering devices independently of the coin receptacle so that a positive check on the number of coins received may be kept by separate individuals so as to ensure absolute accuracy in registering the fund received.

I accomplish the above objects and others which will be more readily understood when taken in connection with the accompanying drawings, wherein;

Figure 1 is a sectional view through the casing and coin receiving compartment showing the relative position of coin registering devices.

Figure 2 is a sectional view taken substantially on the line 2—2 of Figure 1.

Figure 3 is a plan with a portion of the top broken away to show the coin registering device.

Figure 4 is a perspective view.

Referring now to the drawings wherein like reference characters designate corresponding parts throughout the several views, 50 5 designates in its entirety a casing or container having a bottom 6 which is bent upon itself as indicated at 7 to provide and form a rear wall 8, said bottom having side flanges 9, 10, to receive glass panels 11, 12, positioned 55 adjacent the side walls 14, 13, as clearly shown by Figure 2 of the drawings. In

the upper portion of the casing, I have provided a supporting plate 15, having end flanges 16, one of said flanges being disposed adjacent the bottom of a removable door 17 which permits access to the coin registering devices when the door 18, hingedly mounted as indicated at 19 is locked.

It will be noted that the top cover 20 provided with the handle 21 is hingedly connected as at 22 adjacent the rear wall 8 and may be locked by the key 23. The plate 15 forms a partition and divides the device into upper and lower compartments. The coin receiving means in this instance consists of a receptacle 24 removably arranged in the lower compartment and having a plurality of vertical partitions 25 whereby said receptacle is divided into a plurality of coin receiving compartments 26, 27, 28, 29. When the door 18 is opened as shown by Figure 4, the receptacle may be removed and the amount of money found should correspond with the readings of the coin registering devices, now to be described.

With the invention shown, I have provided an independent register 30, supported on the portion of the plate 15 above each compartment. An upwardly extending plate or guide 30 is arranged upon the partition 15 above each of the coin receiving compartments and has a slot in the top thereof to receive a coin inserted through a registering slot 31 in the closure or cover 20, it being observed that the size of the slots correspond with the sizes of the coin to be inserted, namely, nickels, dimes, quarters or half dollars as the case may be. The closure or cover 20 is also provided with an observation opening 32 directly above each register whereby the number wheels thereof may be observed. Extending partially within the guides 30 of each register is one end of an angle lever 33 which is pivoted as at 34, the opposite end of the lever having a small coil spring 35 connected thereto and to the actuating arm 36 which operates the register at the time when a coin is inserted into a respective one of the slots 31. It will thus be seen that when a coin is inserted into any one of the slots and engages against the end of the respective one of the angle levers, the said lever is rocked on its pivot against the resistance of the spring, and a pull will be exerted on the arm 36 thus moving the registering wheel of the register one numeral space as the

coin falls through the slot 31 and through the guide 30 into the respective compartment. The resistance of the spring and the movement of the angle lever 33 is such that an actuation of the arm 36 cannot take place unless the coin is forced entirely through the slot 31 and it will be readily seen that the collector would not actuate the registering mechanism of the coin registering devices unless the coin were actually deposited because otherwise, the inconsistency would appear between the amount of money deposited and the reading on the coin recording devices.

By reason of this construction, it will be readily seen that a careful and accurate check may be made on the funds deposited because one party may retain the key to open the closure 18 for the removal of the coin receptacle 24 and a second party may retain the key to gain access to the coin registering devices to reset the same after a given period.

While I have illustrated and described my invention with some degree of particularity, I realize that in practice various alterations therein may be made. I therefore reserve the right and privilege of changing the form of the details of construction or otherwise altering the arrangement of the correlated parts without departing from the spirit of the invention or the scope of the appended claim.

Having thus described my invention what

I claim as new and desire to secure by 35 United States Letters Patent is:—

A registering collection box comprising a casing including side, rear, and bottom walls and having an opening in its front, a coin receptacle slidably removably fitted within 40 the casing upon the bottom thereof and between the side walls and engaging against the inner side of the rear wall, the said receptacle having partitions therein dividing the same into compartments, a door hinged 45 at the lower side of the open front of the casing, means for locking the door in closed position whereby to prevent access to the said coin receptacle, a partition within the casing above the coin receptacle having slots 50 positioned above respective ones of the compartments of the coin receptacle, a coin registering means upon the partition wall above each of the compartments and having a coin guide for registration with the respective slot in the partition wall, a closure for the top of the casing hingedly connected with a wall thereof, and means for locking the closure in closed position, the locking means being independent of the locking 60 means for the first mentioned door, the said closure for the top of the casing having coin slots therein registering with the upper ends of the coin guides of the respective ones of the registering means.

In testimony whereof I affix my signature.
